FRAME FOR STRETCHING SHADE CLOTH

Filed April 14, 1925

Patented Feb. 22, 1927.

1,618,361

UNITED STATES PATENT OFFICE.

JOHN P. WHITMORE, OF SAN MARINO, CALIFORNIA, ASSIGNOR TO COLUMBIA MILLS INCORPORATED, OF NEW YORK, N. Y., A CORPORATION OF NEW YORK.

FRAME FOR STRETCHING SHADE CLOTH.

Application filed April 14, 1925. Serial No. 23,057.

This invention relates to means for stretching shade cloth or other fabric for the purpose of holding it in place and in extended condition while it is being painted or sized and dried and the main object of the invention is to provide a frame for this purpose which is lighter and more compact than the wooden rail frames heretofore in use. A further object of the invention is to provide a frame for the stated purpose which can readily be kept clean or sufficiently free from adherent paint used in the painting of the shade cloth or other fabric. Another object of the invention is to provide a frame which will interfere to the least possible extent with the proper and thorough application of the paint or sizing medium to the portions of the fabric adjacent the edges where it is attached to the frame.

The invention comprises a shade cloth stretching frame in which the top and bottom rails are wholly of metal and are of such shape and construction to provide for the necessary rigidity in the rails with a minimum of weight and extreme compactness.

The accompanying drawings illustrate my invention and referring thereto:

Fig. 1 is a front elevation of a frame section with shade cloth mounted therein and partly broken away.

Fig. 2 is a vertical transverse section of the upper and lower rails, on line 2—2 in Fig. 3.

Fig. 3 is a partial rear elevation of the upper and lower rails.

Figs. 4 and 5 are vertical transverse sections showing modified forms of the rails.

The invention comprises a frame having upper rails and lower rails connected by suitable stretching bars as hereinafter described, the said rails being in general made in a series of sections which are connected end to end so as to provide for stretching a relatively long piece of shade cloth, Fig. 1 illustrating a portion of the frame including a single section of the upper and lower rails, it being understood that the construction shown for such section is substantially the same throughout the length of the frame.

Such frame section comprises an upper rail 1 and a lower rail 2, said rails being of similar construction but in relatively inverted position as shown in Fig. 2. Each rail comprises a main rail member formed as a flanged metal rail for example a channel

iron as indicated at 3 in Figs. 2 and 3, and a fixed clamp member or clamp plate member 4 formed for example of a strip of sheet metal so as to give the required rigidity, said clamp plate being permanently and rigidly secured adjacent one edge to the rail member 3 by suitable means for example by rivets, indicated at 5, and having its major portion projecting vertically from the rail member so as to provide a relatively thin member for attachment of the cloth. Each clamp plate 4 is provided, at its outer or free edge, that is to say at the lower edge of the upper clamp plate and the upper edge of the lower clamp plate, with a flange or turned over portion 6 forming a groove 7 cooperating with movable clamp means as herein-after described to secure the shade cloth on the clamp member 4. Said movable clamp means may be of any suitable construction, and is herein shown as comprising movable clamp plates 8 having hinged connections 9 for arms or straps 10 which are pivoted or hinged at 11 to plates 12, secured to the rail members 3, for example by rivets or bolts 13 extending through said members 12, 4, and 3. The rail members 3 of the lower rails of adjacent sections are non-rigidly joined together for example by means of fish plates or tie plates 15 at both sides of said rail members, which extend across the joint between the members as indicated at 16, said fish plates being secured rigidly to one of the rail members 3 for example by means of bolts 17 and being pivotally secured to the other of said rail members by bolts 18. The construction is therefore such that the lower rail may be raised or lowered at any of the joints between sections without straining the rail members. The upper rails of adjacent sections may be secured together for example by a fish plate or tie plate 19 and bolts 20 passing through said fish plate and said rail sections. The upper fixed clamp plate members 4 of the adjacent sections may also be secured together for example by means of straps 21 and rivets 22.

Means are provided for forcing or spreading the upper and lower rails apart at the joints of the lower rail after the cloth is secured thereto so as to stretch such cloth. Such means may comprise, for example, spreading arms 24 pivotally mounted on the lower rail members adjacent each joint, for example, by means of the pivot bolts 18

aforesaid or if desired by means of one of the bolts 17, and a lever arm 25 pivotally mounted on the upper rail, for example, by means of U-shaped straps 26 and bolts 27. Each of said lever arms is provided with a pin or stud 28 adapted to engage in any one of a plurality of recesses or notches 29 in the corresponding spreading arm 24, so that downward movement of lever arm 25, with said stud engaged in a suitable notch will cause spreading arm 24 to force the upper and lower rails apart at this point. The above described spreading means are such as are commonly used in the art and any other suitable or well-known means may be used for this purpose.

The frame may be hung or supported in any suitable manner, for example, by means of wire hangers 30 and eye-bolts 31, said hangers depending for example, from means travelling in suitable ways, to permit the assemblage of a large number of the frames in parallel order and of separation of adjacent frames for access thereto in inserting, painting or removing the cloth.

The rail members of the upper and lower rails may be of any suitable shape or cross-section, but are preferably flanged in order to provide maximum strength and rigidity; for example as shown in Fig. 4, said members may comprise angle irons, or as shown in Fig. 5 they may comprise T-bars, to which the fixed clamp plates 4 are secured in any suitable manner, the remainder of the construction being substantially the same as above described.

It will be understood that the frame need not be disposed in a vertical plane but may be arranged in any other suitable position, for example in a horizontal plane. The frame comprises in any case, however, two substantially parallel rails, preferably extending horizontally but not necessarily so, and each comprising a relatively strong rail member preferably flanged and a relatively thin metal clamping member rigidly secured thereto and projecting therefrom toward the other rail and having a groove adjacent its free edge, and a movable clamping member hinged thereon and adapted to cooperate therewith to secure the cloth in position between the rails.

In the operation of the stretching frame above described a strip or sheet of window shade cloth or other fabric to be stretched, indicated at 33, is inserted at its upper and lower edges between the moving and fixed members 8 and 4 of the respective clamping means, the movable clamping members 8 being moved to the position indicated in dotted lines at 8' in Fig. 2 to permit insertion of the edges of the fabric within groove 7 after which said movable clamp members are pushed or snapped into the position indicated in full lines in said Fig. 2, so as to

engage the edges of the fabric as at 32 and hold the same tightly in place. It will be understood that during the insertion of the cloth within the clamping means in this manner the lower rail 2 may be supported at a suitable height in any suitable manner, for example by causing the pin 28 on lever arm 25 to engage in a suitable notch 29 in arm 24 and allowing said arms to rest in a vertical position as shown in dotted lines at 34 in Fig. 1. After the fabric is thus clamped throughout the entire length of the stretching frame the spreading arms are released from engagement and swung to horizontal position, suitable supporting clips indicated at 37 being provided at the back of the respective rails for this purpose, and the sizing medium, for example a suitable glue and water size, is applied to one or both sides of the fabric by means of a brush or in any other suitable manner. As soon as the sizing is applied to an entire strip of cloth, the operator begins the stretching operation at one end of the frame. This is done by swinging the arms 24 and 25 to a position to permit the pin 28 to engage in a higher notch 29 than that with which it originally engaged, as indicated at 35 in Fig. 1, and lever arm 25 is then moved downward so as to push the lower frame 2 downward and stretch the fabric. The arms 24 and 25 are therefore commonly known as stretcher bars. This operation may be repeated if necessary until the proper amount of stretching is obtained. The rails are then held in this position so as to maintain the fabric in stretched condition by bringing the arms 24 and 25 to vertical position with the pin 28 engaged in a suitable notch 29 and the same stretching operation is then repeated at the next joint between the lower rail sections. The entire strip of fabric is thus stretched and kept in stretched condition by engagement of the stretcher bars until the sizing medium has dried, which may require for example from 8 to 12 hours or longer.

When the entire strip of fabric has been sized, stretched, and dried in this manner, the stretcher bars may again be released and allowed to rest on supports 37, as the sized cloth will then retain its stretched condition, assisted only by the weight of the lower rail. The paint to be used may be applied to both sides thereof in the usual manner, for example by means of an ordinary brush and it will be observed, as clearly shown in Fig. 2, that the fixed clamping members 4 being of relatively thin sheet metal and having their major portions projecting from the rail members permit easy access of a brush or other device for applying such paint as well as for applying the sizing medium to the portions of the cloth adjacent the edges at which it is attached to said clamping means.

This is to be distinguished from the type of stretching frames heretofore employed which comprised wooden upper and lower rails which were necessarily of considerable thickness at the edges at which the fabric was secured thereto. With such wooden rails it has always heretofore been extremely difficult to properly and thoroughly apply the paint or sizing medium to the portions of the cloth adjacent the point at which it was attached to the wooden rail since the thickness of such rails at this point prevented ready access of the brush to the cloth. This constitutes an important advantage of my invention. A further advantage results from the fact that the paint or sizing medium and particularly a sizing medium comprising glue or the like, such as is ordinarily used, adheres much less to the metal clamp-
ing members and rail members 3 and 4 than it does to the wooden rails formerly used. In fact when using stretching frames having wooden rails it has generally been found necessary to perform a tedious and time-consuming cleaning or scraping operation to remove the adhered glue or sizing medium from such wooden rails after every two or three stretching or sizing operations, while by the use of stretching frames having metal rail members I am enabled to use the same repeatedly without undue accumulation of glue thereon as the glue upon drying does not adhere strongly to the metal surface of the frame members but scales or falls off readily without requiring manual cleaning or scrubbing.

After application of the paint as above

described the same is allowed to dry upon the cloth, such drying requiring for example from 12 to 24 hours, depending upon the 40 humidity of the surrounding air, and the sized and painted cloth is then removed from the frames. To permit such removal of the cloth the movable clamping members are again opened or moved to the position 45 indicated at 8', such opening operation being easily performed for example by inserting a pointed tool or rod under the edges of the clamps 8 or the straps 10 and prying the same outward past the dead center position. Or, if desired, the main strip of cloth 50 may be removed by cutting along the edges next to the clamps, and the remaining edge portions of the cloth then removed from the 55 clamps.

I claim:

In a stretching frame for shade-cloth a flanged metal rail member, a fixed clamp member consisting of a sheet metal strip secured adjacent one edge to said rail member 60 and having its major portion projecting therefrom, and having its other edge bent to form a groove, and a movable clamp member hinged to said rail member and adapted to engage in said groove to secure the shade-cloth therein, the sheet metal strip affording 65 access to both sides of the cloth fastened thereto in painting such cloth and the metal rail member providing the strength required for stretching the cloth.

In testimony whereof I have hereunto subscribed my name this 6th day of April, 1925.

JOHN P. WHITMORE.
